Primary Examiner — Darlington Ly(74) *Attorney, Agent, or Firm* — ScienBiziP, P.C.(57) **CLAIM**

The ornamental design for a motorcycle, as shown and described.

DESCRIPTION

FIG. 1 is a top-front-left side perspective view of a motorcycle embodying our new design;

FIG. 2 is a top-rear-right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dot-dash broken lines depict a boundary around the de-emphasized elements, which illustrate portions of the motorcycle which form no part of the claimed design.

1 Claim, 8 Drawing Sheets(56)
